6 Claims. (Cl. 260—397.5)

The present invention relates to a chemical process and more particularly to an improved process of converting alkyl aryl ethers to dihydro enol ethers. These latter compounds are suitable for cleavage to β,γ - or α,β -unsaturated ketones and are of particular interest in the steroid hormone field.

The reduction of a phenolic ether to its dihydro derivative, by the action of sodium and ethanol in liquid ammonia was first described by Wooster for anisole. Wooster, U.S. Patent No. 2,182,242. During the past years this reaction has been clarified, improved, and utilized extensively by Birch. Birch, A. J., Quart. Rev., 4, 69 (1950). Under the Birch procedure, the metal, sodium, is added last to the alcoholic-liquid ammonia-phenolic ether reaction mixture. This procedure employing ethanol, liquid ammonia, and sodium proved in practice (1) to work satisfactorily for easily reducible phenolic ethers, (2) to give at best only poor yields with phenolic ethers which are not easily reducible, i.e., phenolic ethers of the only fairly readily and moderately difficult reducible types, and (3) to give substantially none of the desired dihydro products with phenolic ethers of the difficultly reducible type. Examples of alkyl aryl ethers falling within these general classes are: anisole and 2-methoxy-5,6,7,8-tetrahydronaphthalene which are typical of easily reducible compounds; estradiol 3 methyl ether which is a fairly readily reducible compound; 4-cyclohexylanisole and 4-cyclohexylphenoxyethanol which are moderately difficult to reduce; 1-methoxy-5,6,7,8-tetrahydronaphthalene which is difficult to reduce, and di-m-3-(p-methoxyphenyl)-4-(4'-hydroxycyclohexyl)-hexane which is an unusually difficult compound to reduce. With the difficultly reducible 1-methoxy-5,6,7,8-tetrahydronaphthalene (as distinguished from the easily reducible 2-methoxy isomer) Birch reported, for example, that his process gave only a trace of the desired reduction product. Birch, A. J., J. Chem. Soc., 430 (1944).

In our experiments, the application of Birch's conditions to 4-cyclohexylanisole, i.e., addition of sodium metal to a mixture of liquid ammonia, ethanol and phenolic ether, also gave little or no reduction, 95% of the starting ether being recovered.

In attempts to overcome the problems encountered with the non-easily reducible alkyl aryl or phenolic ethers various modifications have been tried. An example of one modification was the use of potassium in place of sodium in the Birch process. This, however, showed little improvement over the use of sodium. With 4-cyclohexylanisole the use of ether, beneficial in other cases of compounds insoluble in ammonia at -33°C ., and replacement of ethanol by methanol or the slower reacting isopropyl alcohol were also all tried but failed to give reduction. Indeed, the latter modification applied to 4-methoxybiphenyl gave some reduction of the non-oxygenated ring affording some unwanted 4-cyclohexylanisole in small yield. With estradiol and hexestrol Birch also found it necessary with his process to prepare derivatives more soluble in ammonia, such as the mono ethers of ethylene glycol and glycerol, in order to obtain reduction even in moderate yields. Birch, A. J., and Mukherji, S.

2

M., J. Chem. Soc., 2531 (1949). Aside from the relatively unsatisfactory yields, this modification possesses the disadvantage of requiring the preparation of special derivatives in place of the less expensive or more readily available methyl derivatives.

In our investigations with the Birch process we tried the hydroxyethyl ether of 4-cyclohexylphenol and obtained some reduction to the desired enol ether, the crude dinitrophenylhydrazone of the unsaturated ketone being isolated in 16% yield after hydrolysis of the enol ether with sulfuric acid. The hydroxyethyl ether of 4-hydroxybiphenyl was also subjected to reduction under the Birch conditions but none of the desired enol ether could be isolated. Interestingly enough, this reaction mixture was found to contain some cyclohexylbenzene, the hydroxyethoxy group having been eliminated during reduction of the oxygenated ring. During our investigations we also tried adding the ethanol last to the blue solution of sodium and 4-cyclohexylanisole in a mixture of liquid ammonia and ether. This modification proved of special interest as the reduction to the desired enol ether proceeded to an appreciable extent, 35% of the dinitrophenylhydrazone of the unsaturated ketone being isolated. This result was especially unexpected as Birch has implied that it was necessary for the alcohol to be present initially in excess, to avoid demethylation. With continued research we then discovered that 4-cyclohexylanisole could be converted to the desired 2,5-dihydro-4-cyclohexylanisole in yields of 84-90%, providing the alcohol was added last and lithium was substituted for sodium. The following general procedure and examples will serve to illustrate our invention.

GENERAL PROCEDURE

A solution of the alkyl aryl or phenolic ether to be reduced is first made in a mixture of liquid ammonia and a dry, inert, organic cosolvent such as diethyl ether or 1,2-dimethoxyethane. This can be conveniently done by dissolving the phenolic ether in the cosolvent and then adding liquid ammonia with stirring. To the resulting homogeneous solution is next added lithium, e.g., in wire form, in small pieces, e.g., over a period of about 1-10 minutes, depending on the quantity of metal. After stirring the resulting blue solution for a short time, e.g., about ten minutes, alcohol, e.g., absolute ethanol, is then slowly added, e.g., dropwise over a period of about fifteen to thirty minutes. As there may be a tendency for foaming to occur near the end of this addition, the use of a reaction flask filled to only $\frac{1}{3}$ up to $\frac{1}{2}$ its capacity is preferred. When the blue color has disappeared the reaction mixture can be worked up in various ways known in the art for recovery of the dihydro product. One of the preferred procedures is to remove the ammonia by evaporation, add ether and water, separate the layers and extract the aqueous layer with ether. The combined organic extracts are then washed, e.g., with saturated salt solution, dried, e.g., over potassium carbonate, sodium sulfate or the like, the ether removed and the desired dihydro or enol ether product isolated from the residue by crystallization or distillation as appropriate.

Example I

2,5-DIHYDRO-4-CYCLOHEXYLANISOLE

A solution of 4.0 g. of 4-cyclohexylanisole in 200 ml. ether was reduced according to the general procedure described above using 250 ml. liquid ammonia, 4.2 g. lithium wire and 37 g. absolute ethanol. Crystallization of the product from dilute ethanol gave the colorless dihydro derivative, M.P. 65-66° in 84-89% yield containing less than 1% unreduced material. Further recrystallization from 90% alcohol raised the melting point to 65.4-66.2°.

SODIUM REDUCTIONS OF 4-CYCLOHEXYLANISOLE

The replacement of lithium by an equivalent amount of sodium in the above procedure gave incomplete reduction; hydrolysis of the enol ether with sulfuric acid and conversion of the enol ether to the dinitrophenylhydrazone of 4-cyclohexyl-3-cyclohexenone indicated 35% reduction. In a variety of runs using ether, methylamine or no cosolvent with the liquid ammonia, employing ethanol or 2-propanol and adding the metal (sodium or potassium) last according to the general procedure of Birch, no reduction occurred, as evidenced by recovery of the starting material and failure to obtain any dinitrophenylhydrazone from the material after the reduction treatment.

When the reduction was carried out in the same way except adding the alcohol to the ammonia-ether solution and adding the lithium last over a ten-minute period, 76% of the dihydro compound, M.P. 64-65.5°, was obtained. This crude material, however, contained 4% of starting material on the basis of ultraviolet absorption.

Example II

REDUCTION OF 4-CYCLOHEXYLPHENOXYETHANOL

Treatment of 4.4 g. of this hydroxyethyl ether in 100 ml. of diethyl ether and 150 ml. liquid ammonia with 2.1 g. of lithium and 18.5 g. ethanol in accordance with the general procedure described above resulted in 62% of crude product, M.P. 46-48°. The conversion of this product to the dinitrophenylhydrazone of 4-cyclohexyl-2-cyclohexenone, M.P. 112-116°, in 68% yield, together with the crude derivative from the oily filtrate, indicated a maximum of 46% reduction with this derivative. Using the general procedure of Birch, except with 2-propanol and ether as cosolvent and adding the sodium last, the extent of reduction was estimated to be 16%, based on the crude dinitrophenylhydrazone, M.P. 115-120°.

Example III

REDUCTION OF 1-METHOXY-5,6,7,8-TETRAHYDRO-NAPHTHALENE

A solution of 20 g. of the methyl ether in 100 ml. 1,2-dimethoxyethane (dried over potassium hydroxide and distilled from sodium) and 400 ml. ammonia was reduced by the general procedure given above, using 6.4 g. of lithium wire, stirring for ten minutes and adding 25 g. absolute ethanol (or 60 g. isopropyl alcohol) over a fifteen to twenty-five-minute period. Distillation of the isolated product gave a crude mixture, B.P. 95-131° (20 mm.) in 83-87% yield. From the absorption maximum at 278 m μ this material contained 8-21% of un-reduced material in the various runs. Conversion to the dinitrophenylhydrazone of the conjugated ketone gave this derivative, M.P. 268° dec., in 55-58% over-all yields from 1-methoxytetrahydronaphthalene.

Example IV

1,4-DIHYDRO-3,17 β -ESTRADIOL 3-METHYL ETHER

The reduction was carried out by the general procedure described above. To a solution of 1.38 g. of 3,17 β -estradiol 3-methyl ether (M.P. 118-119°) in 110 ml. anhydrous ether was added 140 ml. liquid ammonia followed by 1.4 g. lithium wire in small pieces. Ten minutes later 16 ml. of absolute ethanol was added dropwise over a 10-20-minute period. After removing most of the ammonia and carefully adding cold water, the product was extracted with ether, washed with Claisen's alkali (cf. Claisen et al., Ann. 418, 96 (1919)), water, saturated salt solution and dried over sodium sulfate. Crystallization of the product from 6 ml. absolute alcohol and 25 ml. petroleum ether (B.P. 60-68°) gave the desired product with a M.P. 118-119.5° in 90% yield. In other runs the yields ran about 86-99%, the lower yield resulting from the use of 1,2-di-methoxyethane instead of ether.

In a run carried out employing sodium in accordance

with the general procedure of Birch, except for the use of ether and isopropyl alcohol as cosolvents, a solid product, M.P. 97-107°, was obtained in 84% yield. An examination of this crude product by ultraviolet spectrum, however, showed it to contain as much as 28% un-reduced estradiol 3-methyl ether.

Example V

REDUCTION OF 3-(p-METHOXYPHENYL)-4-(4'-HYDROXYCYCLOHEXYL)-HEXANE (HEXAHYDROHEXESTROL MONOMETHYL ETHER)

To 600 mg. of hexahydrohexestrol isomer B (M.P. 132.5-134°) in 10 ml. methanol and 0.8 g. potassium hydroxide in 10 ml. water were added concurrently over thirty minutes and with stirring at 30-35° 3 ml. dimethyl sulfate and 2 g. potassium hydroxide in 5 ml. water. After another thirty minutes ammonia was added, the product was extracted with three portions of ether, the latter washed with Claisen's alkali, water and dried. After evaporation of the ether, the oil was dried to constant weight at 50° and 0.05 mm. In some runs the oil crystallized, micro M.P. 44-53°, but was used without purification.

To the oily methyl ether as prepared above (600 mg.) dissolved in 60 ml. 1,2-dimethoxyethane (dried over potassium hydroxide and distilled from sodium) was added 100 ml. liquid ammonia and 0.6 g. (44 equivalents per mole) lithium wire in portions. After fifteen minutes' stirring enough absolute ethanol (5 ml.) was added (dropwise over 15 minutes) to just discharge the blue color, 15 ml. ammonia and 0.4 g. (29 equivalents per mole) lithium were added and after another ten minutes 3.5 ml. absolute alcohol was added over a ten-minute period. Finally the ammonia was evaporated, ether and cold water added and the product isolated as described above. The desired product was obtained as a neutral oil in a yield of 97%.

The critical features of the invention as illustrated above are (1) the reaction of lithium with an alkyl aryl ether in solution in a mixture of liquid ammonia and an inert cosolvent and (2) followed by the addition of the alcohol. The order in which the reactants are added can be varied as long as the alcohol is added last to the lithium-alkyl aryl ether-liquid ammonia-cosolvent reaction mixture. Optimum conditions for particular reductions may vary but can be readily ascertained by preliminary test. As illustrated in Example V, the process can be repeated by adding to the initial reaction mixture an additional amount of lithium followed by an additional amount of alcohol, etc. Any inert organic cosolvent or mixtures thereof can be employed in the process as long as they are liquid at the reaction temperature (-33°) and increase the solubility of the alkyl aryl ether in the liquid ammonia solution of lithium. Diethyl ether and 1,2-dimethoxyethane are two of the preferred types, the optimum cosolvent for any particular reaction also being readily ascertainable by preliminary test. The alcohols employed can be any of the lower aliphatic alcohols (lower alkanols) such as methanol, n-propanol, isopropanol, etc., or mixtures of the same, although the readily available ethanol is one of the preferred. Alcohols such as tertiary butyl alcohol can also be employed although their use is ordinarily not preferred due to the increased tendency toward foaming during the reaction with the use of the larger molecule alcohols. The alkyl group of the alkyl aryl ethers can be any of the lower alkyl groups such as ethyl, propyl, butyl, amyl, Lexyl, etc., although the use of lower alkoxy groups containing 1 to 6 carbon atoms or less and particularly the readily available methyl (methoxy) aryl ether compounds are preferred. The alkyl group of the alkoxy group as shown above (e.g., Example II) can also contain a hydroxy group or groups.

The reduction takes place in the oxygenated (lower alkoxy phenyl or six carbon) ring of the aryl group to

produce an enol ether or dihydro compound. In other words, one of the three double bonds in the oxygenated six carbon ring is reduced to provide an oxygenated ring containing only two double bonds. These latter compounds as noted above are suitable for cleavage to unsaturated ketones useful in the synthesis of physiologically active compounds.

The improved process of the present invention can be employed to advantage to reduce alkyl aryl ethers and has given markedly superior yields with alkyl aryl ether compounds which are not of the easily reducible type. With the easily reducible compounds the process of the invention gives at least as good yields as the Birch process or modifications thereof known heretofore.

The process of the present invention can be used to advantage to reduce the lower alkoxy substituted aromatic ring of any polycyclic aromatic compound including hydroaromatic polycyclic compounds containing at least one lower alkoxy substituted aromatic ring. All references to melting and boiling points herein are given in ° C.

This application is a continuation of our copending application Serial No. 392,734, filed November 17, 1953, now abandoned.

We claim:

1. The improved process of reducing a R-aryl ether, where R is selected from the group consisting of lower alkyl and hydroxy lower alkyl groups, to the corresponding dihydro enol ether compound which comprises reacting the aryl ether with lithium in a mixture consisting of liquid ammonia and an inert organic solvent by stirring the mixture for a short time, slowing adding

a lower alkanol dropwise to the resulting blue reaction mixture and then recovering the dihydro product from the reaction mixture.

2. The process of claim 1, where the organic solvent is ether and the alkanol is ethanol.

3. The process of claim 1 where the organic solvent is 1,2-dimethoxyethane and the alkanol is ethanol.

4. The process of claim 1 where the alkyl aryl ether is a methyl aryl ether.

5. The process of converting a six carbon aromatic ring having a lower alkoxy group attached thereto, to the corresponding dihydro ring compound which comprises reacting said ring with lithium in a mixture consisting of liquid ammonia and an inert organic solvent by stirring the mixture for about ten minutes and then adding a lower alkanol dropwise over a period of about fifteen to thirty minutes to the resulting blue reaction mixture.

6. The process of preparing 1,4-dihydro-3,17 β -estradiol 3-methyl ether which comprises reacting 3,17 β -estradiol 3-methyl ether with lithium in a mixture consisting of liquid ammonia and an inert organic solvent by stirring the mixture for about ten minutes and then adding a lower alkanol dropwise over a ten to twenty minute period to the resulting reaction mixture.
